UNITED STATES PATENT OFFICE.

CHARLES D. HAZEN, OF PAINESVILLE, OHIO.

PERMUTATION LOCK.

Application filed August 24, 1923. Serial No. 659,094.

To all whom it may concern:

Be it known that I, CHARLES D. HAZEN, a citizen of the United States, residing at Painesville, in the county of Lake and State 5 of Ohio, have invented a certain new and useful Improvement in Permutation Locks, of which the following is a full, clear, and exact description.

This invention relates to a permutation 10 lock capable of various uses, but herein shown applied to the steering post of an automobile, and also to the transmission controlling lever of an automobile.

It is the object of the invention to provide 15 a permutation lock which is simple in construction, economical to manufacture, and easy to assemble, and which can be conveniently operated by one knowing the combination, and which is safe against tampering 20 or unlocking by unauthorized persons.

A further object is to provide a lock in 25 which it is impossible to obtain access to the interior of the casing when the locking elements are in locking position. A further 30 object is to provide a lock which can be readily adjusted for any desired combination.

A further object is to provide a lock which 35 may be locked by any one of many different settings of the lock actuating members, and unlocked, by restoring the particular members moved, to their original positions, so that the combination cannot be obtained by 40 watching the unlocking operation. A further 45 object is to provide a permutation lock which can be locked in various ways, and which can be readily unlocked by a person having knowledge of the basic combination regardless of the manner in which it has 50 been locked.

The above and other objects of the invention are accomplished by the means shown in the accompanying drawings and described in the following specification, and 45 specifically defined in the claims, and the invention may be said to comprise the mechanism herein shown, described and claimed, together with such modifications thereof as will be obvious to those skilled in the art.

50 Reference should be had to the accompanying drawings forming a part of this specification, in which Fig. 1 is a fragmentary, sectional view showing the improved lock applied to the steering post of an automobile; Fig. 2 is a view of the lock shown in Fig. 1, partly in horizontal section and

partly in elevation; Fig. 3 is a sectional view showing the interior locking mechanism in elevation; Fig. 4 is a view showing the lock bolt in side elevation; Fig. 5 is a vertical 60 section showing the improved locking mechanism applied to the transmission controlling lever of an automobile; Fig. 6 is a plan view of a modified form of lock, partially 65 broken away to show one of the locking elements in section.

Referring to Figs. 1 to 4 of the drawing, in which the lock is shown applied to the steering post 1, is mounted within the usual fixed 70 steering column 2, and has rigidly clamped thereto a locking collar 3, which co-operates with the locking mechanism in securing the steering post 1 to the fixed column 2. The locking mechanism is mounted within a cylindrical casing 4, which is formed integral 75 with a section 5 of the steering column. The outer end of the cylindrical casing 4 is closed by means of a cover plate 6, and centrally of the casing—there is mounted a sliding lock bolt 7 which has an inner enlarged end 8 which projects through, and has a sliding fit in an opening in the bottom 80 of the casing 4, and is adapted to be engaged in a suitable recess 9 formed in the 85 locking collar 3.

At the outer end of the enlarged portion 8 the lock bolt is provided with a circumferential flange 10, and outside the flange 10 the bolt is provided with additional circumferentially spaced flanges 11 and 12. 90

Outside the inner enlarged portion 8, the body portion 13 of the lock bolt is of reduced diameter, and the outer end of the portion 13 has a sliding fit in a central opening of the cover 6. The flanges 10, 11 and 12 of the lock bolt are located within the casing 4, and between the innermost flange 10 and the bottom of the casing there is interposed a compression coil spring 14 which serves normally to hold the locking bolt in retracted position clear of the locking collar 3. When the locking bolt is so retracted, the steering post 1 is free to turn. When, however, the locking bolt is held in its inmost position with the end thereof in the recess 9 of the collar 3, the steering post 1 is locked against rotative movement. 100

The present invention resides in the means employed for retaining the locking bolt 7 in locking position. 110

The locking elements 15 which serve to

hold the locking bolt in locking position are mounted within the casing 4, and each locking element 15 is adapted to be moved to engage with the outer face of one of the flanges 10, 11 or 12. The locking elements 15 are arranged in a plurality of sets which are spaced circumferentially around the central locking bolt 7 within the casing 4.

The locking elements 15 of each set are superposed and rotatable about a common axis, one of the locking elements of each set being engageable with one of the flanges of the locking bolt. Each of the locking elements 15 has a projecting locking portion 16, which in one position of the locking element engages with a flange of the locking bolt. The projecting portion 16 is also engageable with the cylindrical wall of the casing 4 to limit the movement of the locking element in one direction. Each locking element 15 is also provided with a projecting pin 17 which is engageable with the cylindrical wall of the casing to limit the movement of the locking element in the opposite direction. When the locking element has been rotated to a position in which the projecting portion 16 engages the cylindrical wall, the locking element is disengaged from the flange of the locking bolt. When the locking element has been rotated to bring the pin 17 into engagement with the cylindrical wall, the projecting portion 16 will be in locking position.

Each of the locking elements 15 has two circumferentially spaced recesses 18, in either of which the pin 17 may be placed. When the pin 17 is placed in one of the recesses 18, the locking element may be moved to locking position by turning to the right, and when the pin 17 is placed in the other recess 18, the locking element is moved to locking position by turning to the left.

Each of the innermost of the locking elements 15 of each set is fixed to a stem or shaft 19, the inner end of which is journaled in a recess formed in a plate 20 which fits against the bottom of the casing, and the outer end of which extends through the cover plate 6, the outer end of the stem 19 being provided with an enlargement or knob 21 to facilitate the manual operation thereof.

The next outer locking element 15 of each set is fixed to the inner end of a sleeve 22 which is rotatably mounted upon the stem 19, projects through the cover 6, and is provided with a suitable enlargement or knob 23 at its outer end. The outermost locking element 15 of each set is fixed to the inner end of a sleeve 24 which is rotatably mounted upon the sleeve 22, projects through the cover plate 6, and is provided with an enlargement or knob 25 at its outer end.

By means of the three superposed knobs 19, 23 and 25 of each set, any or all of the

locking elements may be turned to locking position. Immediately outside the two inner locking elements are fixed partitions 26 and 27 which serve to retain the locking elements in proper position and to hold the locking elements against outward movement while engaged with the locking bolt.

The locking elements are preferably yieldingly mounted to facilitate their engagement with the flanges of the locking bolt, springs 28 being interposed between the partition 26 and the innermost locking elements 15, and springs 29 being interposed between the partition 26 and the next outer locking elements 15, and springs 30 and 31 being interposed between the outermost locking elements and the partition 27 and between the outermost locking elements and the cover plate 6.

All of the locking elements 15, together with the inner plate 20 and partition members 26 and 27 are carried by the cover plate 6, and are removable from the casing bodily therewith. The cover plate 6 is secured in place on the casing 4 by means of short screws 32 extending through the outer edge portion of the cylindrical wall into the edge of the cover plate, and the lock mechanism is secured to the cover by means of long screws 33 which extend through the cover plate 6, partition members 26 and 27, and are screwed into the detachable bottom plate 20 which rests upon the bottom of the casing, the partition plates 26 and 27 being held in position by means of sleeves 35 mounted upon the screws 33.

In order to prevent the removal of the locking mechanism when the steering post is locked, a stud 36 projects into the interior of the casing adjacent each of the locking elements 15. The partition members are provided with suitable notches to permit the passage thereof past the stud 36, and the locking elements 15 are provided with notches 37 which register with the studs 36 only when the locking elements are in unlocking position.

In order to permit the removal of the locking mechanism from the casing, it is therefore necessary that the locking elements 15 be in unlocking position.

The locking elements 15 will preferably have their stop pins 17 so adjusted that some of them will be moved to locking position by turning in one direction, and others by turning in the opposite direction. To lock the steering post, the steering wheel will be turned to position the recess 9 in the collar 3 in alignment with the enlarged end 8 of the locking bolt, and the locking bolt will be entered into the recess 9 by pushing it inwardly against the action of the spring 14. The locking bolt may be then locked in its locking position by turning any one of the locking elements 15 into engagement with one of the flanges of the locking bolt.

After turning the first locking element into engagement, one or more of the other locking elements will preferably be turned to locking position. By remembering which of 5 the knobs he has turned, the driver may unlock the steering post by turning to reverse position the knobs which he actuated in locking. Should the driver forget which knobs he has actuated, he can readily unlock 10 the steering post if he knows the combination.

To unlock the device under these conditions, he will simply turn to the left each 15 of the knobs set for unlocking, by turning to the left, and turning to the right all of the other knobs.

By reason of the fact that the driver will ordinarily in unlocking, operate only the knobs which he has turned in locking, which 20 may be any combination, it is impossible for any one to learn the combination by watching the unlocking operation.

In Fig. 5 of the drawing, a locking mechanism the same as that above described, is 25 shown applied to the gear shift lever 38 of an automobile. The gear shift lever 38 extends through the casing 39 which is secured to the member in which the lever is mounted and also serves as a housing for the locking 30 mechanism, the lever 38 being provided with circumferential flanges 10^a, 11^a, within the casing, and the upper end of the casing being closed by means of a detachable cover 35 plate 6^a, similar to the cover 6 in the modification first described.

The lever 38 is locked against movement by means of any one of a series of locking elements 15^a corresponding exactly to the locking elements 15 above described, which 40 are mounted to move into and out of engagement with the flanges 10^a, 11^a, of the lever 38.

The elements 15^a are arranged in sets upon 45 opposite sides of the lever 38, and are fixed to rotatable stems 19^a and 22^a, corresponding to the stems 19 and 22 in the modification first described, the inner and outer locking elements being held in proper position 50 within the frame by means of partition members 26^a and 27^a. When any one of the locking elements 15^a is in locking position engaging a flange of the lever 38, the lever is locked against movement, the operation 55 of the locking elements 15^a being exactly as described above in connection with the steering post lock.

Referring to Fig. 6 of the drawing, the casing 4^a which is polygonal in shape, corresponds to the casing 4 in Fig. 1 and may 60 be formed as a part of the steering column of an automobile. A flanged lock bolt 13^a corresponding exactly to the lock bolt 13 in Fig. 1 is mounted centrally of the casing 4^a and the flanges thereof, the outer flange 65 12^a, only, being shown, are engaged by lock-

ing bolts 40 which extend laterally into the casing, a lock bolt for each flange being provided through alternate faces of the polygonal casing. Each of the lock bolts 40 is provided with a coarse threaded portion 70 41 which engages internal threads in a bushing 42 screwed into a tapped opening in the casing wall. The bolt 40 has an outer squared reduced end portion 43 which fits slidably in a square socket in a stem 44 75 which projects outside the casing. The stem 44 has a flange 45 at its inner end which is loosely clamped against the outer end of the bushing 42 by means of a gland nut 46 whose outer face is substantially 80 flush with the outer surface of the casing.

Attached to the outer end of the stem 44 is a knob 47, the inner end of which covers the nut 46 and prevents access thereto.

When one of the stems 44 is rotated by 85 turning its knob 47 the bolt 40 will be moved inwardly into locking engagement with a flange of the lock bolt 13^a or outwardly to a position clear of the flange, depending on the direction of rotation, the movement inwardly being limited by engagement of the shoulder at the inner end of the threaded portion 41 with a flange of the lock bolt and the movement outwardly being limited by engagement of the shoulder at the outer end 90 of the threaded portion 41 with the inner end of the stem 44. In each of these locks certain of the bolts 40 will be provided with left hand threads and the others with right hand threads. As in the modifications above 95 described the device may be locked by turning any knob or by turning a number of selected knobs and may be unlocked by turning these knobs in a reverse direction, and the device may be unlocked by any person knowing the combination by turning each knob to the limit of its movement in the unlocking direction. Whenever it is desired to change the combination the right and left locking bolts may be interchanged in any 100 desired manner or any of the locking bolts may be replaced by a reversely threaded bolt.

Having described my invention, I claim:

1. A permutation lock comprising a casing, a shiftable member extending through the casing, a plurality of locking elements within the casing and movable into and out of engaging position with respect to the shiftable member, a stop device associated with each locking element, each stop device being adjustable for changing the direction of movement of its locking element to engaging position, and actuating means for said locking elements.

2. A permutation lock comprising a casing, a shiftable member having a shouldered portion within the casing, a plurality of locking elements rotatably mounted alongside the shouldered portion of the shiftable member, each of said locking elements hav-

ing a projecting portion and being movable through a partial revolution to bring said projecting portion into and out of engagement with the shouldered portion of the 5 shiftable member, said projecting portions being engageable with the casing to limit the turning movement thereof in one direction, and a second projection carried by each locking element to limit its movement in 10 the opposite direction.

3. A permutation lock comprising a casing, a shiftable member extending into the casing, a plurality of locking elements rotatably mounted within the casing, means 15 for limiting the movements of said elements whereby each is movable through a partial revolution and from a position clear of the shiftable member to a position in engagement therewith, certain of said locking elements being movable to engaging position by a rotative movement in one direction and other of said locking elements being movable to engaging position by a rotative movement in the opposite direction, and separate 20 means for actuating each of said locking elements.

4. A permutation lock comprising a casing, a shiftable member extending into the casing, a plurality of locking elements rotatably mounted within the casing, each of 25 said locking elements having a projection adapted to be moved into locking position with respect to the shiftable member and to engage a portion of the casing on either 30 side of the shiftable member, a stop carried by each locking element and engageable with the casing when the projection is in locking position, said stop being adjustable to permit the projection to be positioned on either 35 side of the shiftable member, and separate 40 means for actuating each of the locking elements.

5. In a permutation lock, a casing, a cover 45 for the casing, means for detachably securing the cover to the casing, a shiftable member, a plurality of locking elements within the casing and carried by the cover, said locking elements being movable into and out 50 of engagement with said shiftable member, separate means upon the outside of the cover for actuating each of the locking elements, and means carried by the casing and engageable with certain of said locking elements to prevent removal of the cover except 55 when said elements are in unlocking position.

6. In a permutation lock, a casing, a cover 60 for the casing, means for detachably securing the cover to the casing, a plurality of rotatably mounted locking elements within the casing carried by the cover, stems fixed to the locking elements and projecting through the cover, and a projection carried by the casing engageable with certain of 65 said locking elements to prevent removal

of the cover and locking elements from the casing, said last mentioned locking elements having notches which are aligned with said projection when the locking elements are in 70 unlocking position.

7. A permutation lock comprising a casing, a shiftable member having shouldered portions within the casing, and a plurality of superposed rotatably mounted locking elements within the casing movable into and 75 out of engagement with the shouldered portions of the shiftable member, the innermost of said locking elements having a stem projecting through a wall of the casing, and an outer of the locking elements having a 80 stem in the form of a sleeve surrounding said first mentioned stem.

8. A permutation lock comprising a casing, a shiftable member having shouldered portions within the casing, and a plurality 85 of superposed locking elements mounted for rotation about a common axis into and out of engagement with the shouldered portions of the shiftable member, the innermost of said locking elements having a cylindrical 90 stem projecting through a wall of the casing, and an outer of the locking elements having a stem in the form of a sleeve surrounding said first mentioned stem, said stems having enlarged portions upon the 95 outside of the casing to facilitate manual actuation of the locking elements.

9. A permutation lock comprising a casing, a shiftable member having a plurality 100 of annular flanges within the casing, and a plurality of sets of locking elements engageable with said flanges, each set comprising a plurality of superposed locking elements mounted for rotation about a common axis into and out of engaging position with respect to said flanges, the innermost locking elements of each set having a cylindrical 105 stem extending through a wall of the casing, the outer locking elements of the sets having stems in the form of sleeves surrounding the first mentioned stems, said stems having enlargements at their outer ends outside the 110 casing.

10. A permutation lock comprising a casing, a shiftable member mounted centrally 115 of the casing and having a plurality of circumferential flanges within the casing, and a plurality of locking elements within the casing spaced about the periphery of the flanges, each locking element being adapted 120 to be turned into and out of locking engagement with one of the flanges, each of said locking elements having a stem projecting through a wall of the casing.

11. A permutation lock comprising a casing having a cover, a shiftable member mounted centrally of the casing and having a plurality of circumferential flanges within the casing, and a plurality of locking elements within the casing spaced about the 125 130

periphery of the flanges, the locking elements being rotatable about parallel axes and each having a projection adapted to overlie a portion of one of the flanges of the shiftable member, each locking element having a stem projecting through the cover.

12. A permutation lock comprising a casing, a shiftable member mounted centrally of the casing and having a circumferential flange within the casing, and a plurality of locking elements within the casing and spaced about the periphery of the flange, said locking elements being rotatably mounted and each having a projection adapted to engage the flange and a stem projecting through a wall of the casing, and means for limiting the turning movements of each of the locking elements in both directions, said locking elements at one limit of their movement engaging said flange and at the other limit of their movement lying clear of said flange.

13. A permutation lock comprising a casing, a shiftable member mounted centrally of the casing, a plurality of locking elements adapted to be individually moved into locking engagement with the shiftable member at different points along the length thereof, other locking elements adapted to engage the shiftable member at points spaced circumferentially with respect to the points of engagement of the first mentioned elements, and separate means for actuating each of said locking elements.

14. A permutation lock comprising a casing, a shiftable member mounted centrally of the casing, a series of locking elements adapted to be individually moved into locking engagement with the shiftable member at different points along the length and circumferentially of said shiftable member, separate means for actuating each of the locking elements, and means associated with each of said locking elements for reversing the direction in which the actuating means is moved to shift the locking element to engaging position.

15. A permutation lock comprising a casing, a shiftable member mounted centrally of the casing, a series of locking elements adapted to be individually moved into locking engagement with said shiftable member, and a plurality of sets of concentrically arranged rotatably mounted actuating members for said locking elements, each of said actuating members being adapted to shift a locking element into and out of locking engagement with the shiftable member, certain of said actuating members moving the locking element associated therewith to unlocking position by turning in one direction, and other of said actuating members moving their locking elements to unlocking position by turning in the opposite direction.

16. A permutation lock comprising a casing, a locking bolt mounted in the casing, a plurality of locking elements within the casing, each movable to engaging and disengaging positions with respect to the locking bolt, an adjustable stop member associated with each locking element, and separate means extending through a wall of the casing for actuating each locking element.

17. A permutation lock comprising a control lever, having laterally extending projections thereon, a casing surrounding the lever and enclosing the projections, a series of separate rotatably mounted locking elements within the casing, each adapted to engage a projection on the lever to lock the same, and separate actuating means for each of said locking elements.

18. In a permutation lock, a casing, a locking bolt slidably mounted in a wall of the casing, said bolt being rotatably mounted and having a threaded engagement with a part fixed to the casing, and a stem rotatably mounted in the casing and extending outside the same, said stem being slidably but nonrotatably connected to the bolt.

In testimony whereof, I hereunto affix my signature.

CHARLES D. HAZEN.
